UNITED STATES PATENT OFFICE.

JOHN H. HUNT, OF DAYTON, OHIO, ASSIGNOR TO THE DAYTON ENGINEERING LABORATORIES COMPANY, A CORPORATION OF OHIO.

BURNER.

Application filed March 27, 1919. Serial No. 285,662.

To all whom it may concern:

Be it known that I, JOHN H. HUNT, a citizen of the United States of America, residing at Dayton, county of Montgomery, State of Ohio, have invented certain new and useful Improvements in Burners, of which the following is a full, clear, and exact description.

This invention relates to fuel feeding systems for liquid fuel burners, wherein the fuel is supplied to the burner by air pressure.

One object of the invention is to provide improvements in the manner of control of the air pressure which forces the fuel to the burner from a source of fuel supply, so that the air pressure may be adjusted to a relatively fine degree.

Other and further objects and advantages of the present invention will be apparent from the following description, reference being had to the accompanying drawings, wherein preferred embodiments of the present invention are clearly shown. These embodiments constitute improvements in apparatus disclosed in the copending application of John Good, Serial No. 195,506, filed October 9, 1917.

In the drawings:

Fig. 1 is an end elevation, partly in section of a burner constructed in accordance with the present invention;

Fig. 2 is a side elevation of the blower for the burner together with a section of the burner taken on the line 2—2 of Fig. 1;

Fig. 3 is a fragmentary view of the burner showing a modified form of one of the parts thereof; and

Figs. 4 and 5 are sectional views similar to Fig. 2, showing modified forms of the invention.

Referring to the drawings, 20 indicates as a whole the burner and 21 the blower. The burner 20 includes a body or casing 22 which forms an air receiving chamber. Body 22 is directly connected with the blower which may be of the centrifugal type and is driven by an electric motor or other suitable power device 23. Within the body 22 is mounted a shell 24 in which the combustion of the fuel takes place. The space between the shell 24 and the body 22 forms an air receiving chamber 25. The chamber 26 within

the shell 23 will be known as the combustion chamber.

Air for combustion purposes will pass from the chamber 25 into the combustion chamber 26 through a series of slits which may be arranged in any fashion which will insure a good mixture of the air with the fuel; as for example, some of these slits may be arranged as shown at 27, diametrically opposite one another, and others in spiral fashion as shown at 28, or only spirally arranged slits may be used as shown in Figs. 4 and 5. Instead of these elongated passages, a series of spirally arranged round holes, as shown at 30 in Fig. 3, may be provided for the entrance of combustion air to the chamber 26. Air for fuel atomizing purposes passes through the chamber 25 through a small passage 31 arranged in alignment with the flow of air from the blower into the chamber 25.

A fuel reservoir 40, provided with a fuel opening 41 closed by screw stopper 42, is supported by a hollow neck 43 having a flanged portion 44 by means of which the neck is detachably secured to body 22. Flanged portion 44 provides a closure for an opening 29 in the wall of body 22 and provides the top wall of fuel reservoir 40. The chamber included within the neck 43 and above the level of the fuel indicated at 45 will be known as the fuel pressure chamber. Chamber 46 communicates with chamber 25 through an air duct or passage 47 provided in flanged portion 44, the opening of which is adjusted by means of the screw 48. A bleeder passage 49, provided in neck portion 43, connects the chamber 46 with the outside atmosphere. The fuel delivery pipe 50 extends from near the bottom of the reservoir 40 to a point approximately on the level of the passage 31 in the shell 24.

The ignition of the fuel is provided for electrically by means of a spark plug 60 which is connected with suitable ignition apparatus, not shown, the particular construction of which forms no part of this invention.

The operation of the burner is as follows:

The motor 23 operates the blower 21 which drives air under pressure into the air receiving chamber 25, from which a part of the air

will pass through the passages 27 or 28 into the combustion chamber 26 there to be mixed with atomized fuel and to be consumed. Before air can be admitted into the fuel pressure chamber 46 from the chamber 25, the pressure of the air must be reduced, otherwise the fuel will be forced out of the pipe 50 at too rapid a rate and under too great a pressure. This reduction in pressure is accomplished through the combined effect of the passages 47 and 49. Obviously, a part of the air entering chamber 46 will be expelled to the atmosphere through the passage 49. By adjusting the relation of the opening of passage 47 to the passage 49 the required amount of reduction of air pressure in the chamber 46 can be obtained.

The air above the fuel level 45 in the reservoir 40 being under pressure in the manner described, the fuel will be forced upwardly at the desired rate and under the desired pressure to a point approximately at the level of the passage 31, from whence the fuel will be blown out in the form of a spray of small particles towards the incoming combustion air, by means of the air passing through the atomizing orifice 31. This fuel is ignited electrically by means of a spark from the plug 60. The resulting flame may extend out considerably beyond the burner body 22 according to the pressure maintained within the burner. In order to use this flame for heating purposes, the burner body may be attached to any suitable combustion tube by means of bolts 22. This combustion tube may be in contact with water or air or any other suitable heat transferring medium.

Fig. 4 shows a form of the invention wherein the fuel reservoir is located at a distance below the burner so that fuel and air pipes are required. The casing 25 is provided with an externally threaded boss 59 which is centrally bored to provide for nozzle 61 having a shoulder 62 fitting against the lower end of boss 59. Shoulder 62 is beveled to fit against the flared upper end of fuel pipe 63 which extends down to near the bottom of reservoir 64. A nut 65 having threaded engagement with boss 59 is centrally bored to provide for the extending therethrough of pipe 63, and is provided with an annular ledge 66 which supports a disc 67. Disc 67 is centrally bored and countersunk to receive the flared upper end of pipe 63 and to effect a tight joint between nozzle 61 and pipe 63 when the nut 65 is screwed upwardly on boss 59. Boss 59 is provided with air duct 68, through which air may pass to the space above disc 67, thence through passages 69 in disc 67, down around the pipe 63 and thence to reservoir 64 through air pipe 70 which is clamped to the lower end of nut 65 by nut 71.

The duct 68 is controlled by screw 72 and

the required pressure reduction below the pressure in air chamber 25 for fuel elevating purposes is obtained by the cooperation of this manually controlled duct 68 and a bleeder passage 73 drilled in the nut 65, as described in connection with passages 47 and 49 shown in Fig. 2.

This construction provides for the concentric relation of pipes 63 and 70 so that in the installation of the burner only one pipe connecting the burner and reservoir is visible.

In Fig. 5 is shown a construction wherein the fuel and air pipes are separately connected with the burner and reservoir. Fuel pipe 80 extends directly from reservoir 64 up through the body 22 and is provided with a nozzle 81 extending into the burner. Air chamber 25 is connected with reservoir 64 by air pipe 82 and valve 83. Valve 83 is provided with air duct 84 controlled by screw 85, and with a bleeder passage 86. The manually controlled duct 84 and bleeder 86 cooperate in the manner previously described to control the air pressure in reservoir 64 required for fuel elevating purposes.

In each of the forms of the invention illustrated and described, the pressure in the fuel reservoir can be controlled to a comparatively fine degree of adjustment, which is necessary to the successful operation of the burner. This result is accomplished through the cooperation of the manually controlled duct and the bleeder passage which are so related that to vary the pressure in the reservoir the adjusting screw must be turned through a relatively large angle.

While the forms of mechanism herein shown and described constitute preferred forms of embodiment of the invention, it is to be understood that other forms might be adopted, all coming within the scope of the claims which follow:

1. In a liquid fuel burner, the combination with a body including an air chamber; of a fuel reservoir; a member detachably secured to the body and supporting the reservoir and provided with a passage from the air chamber to the reservoir; and a nozzle extending from the reservoir into the burner.

2. In a liquid fuel burner, the combination with a body having an air chamber; of a part attached to the body and having an air passage communicating with the air chamber; a fuel reservoir supported by said part and in communication with said air passage and air chamber; and a nozzle extending from the fuel reservoir to the burner.

3. In a liquid fuel burner, the combination with a body having an air chamber and an opening in a wall thereof; of a part detachably secured to the body and providing

- a closure for said opening, said part having an air passage leading to said air chamber; a fuel reservoir supported by said part; and a nozzle extending from the reservoir into the burner.
4. In a liquid fuel burner, the combination with a burner body including an air chamber and having an opening in a wall of the air chamber; of a fuel reservoir including a neck portion and a flanged portion providing the top wall of the reservoir, said flanged portion being secured to the body and providing a closure for said opening, said flanged portion being provided with a duct leading from the air chamber to the reservoir, and said neck portion being provided with a bleeder passage; and a nozzle extending from the reservoir to the burner.
5. In a liquid fuel burner, the combination with a body having an air chamber and an opening in a wall thereof; of a part detachably secured to the body and providing a closure for said opening, said part having an air passage leading to said air chamber; a fuel reservoir supported by said part; and a nozzle concentric with said part and extending from the reservoir into the burner.

In testimony whereof I affix my signature.

JOHN H. HUNT.
